PRINTING TELEGRAPH APPARATUS

Reginald Dennis Salmon and Alan Arthur Kirchel, Croydon, England, assignors to Creed and Company Limited, Croydon, England, a British company

Application August 11, 1943, Serial No. 498,190
In Great Britain August 14, 1942

12 Claims. (Cl. 178—27)

This invention relates to printing telegraph receivers and more particularly to the mechanism for selecting a function to be performed, as distinct from selecting a character to be printed.

The selection of a function is commonly performed by means of combination members, set in accordance with the received signal elements, which allow a spring actuated selector member to move towards the combination members, e. g. into a series of aligned slots in such members. It has hitherto been usual to provide that the selector member, in moving towards the combination members, positioned an interposing member in the path of a bail or other cam operated member and it was thus necessary for the selector member to remain in its forward position until the performance of the function was definitely determined. The selector member must then be withdrawn from contact with the combination members in order to allow of the combination members being set in accordance with the elements of the next signal. The time allowed for this sequence of operations is limited, and the movements of the selector members into and out of selected position must therefore take place with great rapidity. This is a source of noise and wear in operation.

It is an object of the invention to reduce the noise and wear of the function selecting mechanism.

According to one feature of the present invention we provide a printing telegraph receiver in which a selector member is allowed to be moved by a spring in one direction to select a function to be performed and is moved in the other direction to initiate the performance of the selected function.

In this manner, the movements of the selector members can be less rapid and therefore less noisy, since the time allotted to both movements can include a large fraction of the time formerly taken by the movement of the cam operated member.

Among the functions normally provided in page printing telegraph apparatus are printing, letter spacing, figure shift, letter shift, paper line feed, carriage return, sending of an "answer back" signal from an associated transmitter in response to the "who are you" signal, and the like. The printing and the letter space functions are usually treated in an entirely different manner from the remainder of the functions. It also frequently happens that it is desired to provide for the performance of some additional function in an existing apparatus, and this is performed

then arranged to be carried out in some manner which is different from that in which the other functions are carried out; and it may even be that the additional function in question must be selected in a manner different from that in which other functions are selected.

It is a further object of the present invention to provide function selecting and initiating apparatus in which all functions may be selected and their performance initiated in a generally similar manner, so that it will be easy to add other functions, should that be necessary, in a convenient and simple manner without having recourse to what in effect amount to mechanical subterfuges such as exist on many if not all existing apparatus.

Other features of the invention will appear from the following description and the claims.

In carrying out the main object of the invention, we provide a selector bar for each function, which is allowed to move in one direction and then positively moved in the other direction carrying with it in this last mentioned movement a secondary bar which initiates the performance of the function. In most cases the selector bar is only allowed to move in the first direction when the function is selected for performance, but since the functions of printing and letter spacing are required in the great majority of selections, the selector bars for these functions are moved invariably and invariably carry with them their corresponding secondary bars in the other direction. In the few cases in which printing or letter spacing is not to be performed, this is because some other function has been selected and means is provided therefore for causing the selection of this last mentioned function to arrest the movement of the secondary bar for the printing and/or letter spacing function before it has travelled far enough to initiate the performance of its function.

The nature of the invention will be better understood from the following description taken in conjunction with the accompanying drawings in which

Fig. 1 is an expanded perspective view of the function selecting and initiating mechanism of a page printing telegraph apparatus showing some of the function bars;

Fig. 2 shows the printing and letter space function mechanisms;

Fig. 3 shows two function selecting bars, each of which suppresses either the printing function or the letter space function but not both; and

Fig. 4 shows the function mechanism by which

the release and arrest of a reperforator is controlled.

Referring to the drawings, 1, 2, 3, 4, and 5 denote combination bars which are set in accordance with received signal elements by means of levers 51 and cams 52 in the manner described in British Patent No. 482,048. Pivoted to the left hand ends of these bars are levers 100, each formed with a forked member embracing a rod 41. When the combination bars are moved lengthwise, the forked levers 100 can slide on rod 41. At the conclusion of setting a cam 101 acts on a bellcrank lever 43 to cause a hammer 56 on each of the levers 100 to strike one or other of two horizontal portions of detent levers 111 or 112 (parts only of which are shown) controlling the release of a disc as described in United States Patent No. 2,127,145, issued to Salmon on Aug. 16, 1938. Each disc controls the movement of the planet wheel of a sun and planet element of an aggregate motion translating mechanism which positions a type wheel 102, Fig. 2 for a selected character to be printed. The type wheel 102 is in the form of a type cylinder which is selectively rotated and moved longitudinally by means of two mechanical aggregate motion systems as described in British Patent No. 441,090, although differing from the latter in that the two aggregate motion systems are, as stated above, sun and planet gear systems. For the purpose of printing the type cylinder 102 is carried in a frame 103 which is moved parallel to a paper platen 104 by means of a pinion 105 engaging a rack 106. The pinion 105 is rotated one tooth at a time by a worm gear 107 on the same shaft which is rotated by a worm 108 through a friction clutch (not shown) but is normally held stationary until released for one revolution. The frame 103 is moved to bring the type cylinder 102 against the platen 104 for printing by the action of a printing cam 109 driven through a friction clutch but normally held stationary. The printing mechanism is generally similar to that described in British Patent No. 441,090 and is also similar thereto in that the movement of the type cylinder axially in accordance with figure shift or letter shift signals is performed by an additional element (sun and planet in the case considered) of one of the aggregate motion systems. The letter spacing is, however, not carried out as described in British Patent No. 441,090 but in a manner that will presently appear.

A plurality of selector members 6, 7, 8, 9 (Fig. 1), 10, 11 (Figs. 2 and 3), 12, 13 (Fig. 3), and 14, 15 (Fig. 4) is provided, one for each function to be performed. These members differ from one another in the arrangement of projections thereunder. The selector bars 10 and 11, allotted to the letter spacing and printing functions, are not provided with any projections thereunder. The other selector bars are provided with projections thereunder which co-act with notches in the combination bars 1 . . . 5 and in additional combination bars 25 and 26. The selector bar 9, for example, is for the figure shift function and is provided with projections which co-act with notches in the combination bars 1 . . . 5 and the same applies to selector bar 7, which is allotted to the "all negative" signal. The selector bar 6 which may be regarded as a typical selector bar for a function to be selected after all the bars 1 . . . 5 and 25 and 26 have been set has projections co-acting with notches in all these bars.

Each selector bar 6 . . . 15 is urged to the right

by a spring such as 6f and its right hand end rests against a common bail 20. When the combination bars 1 . . . 5 have been set the bail 20 is moved to the right by a cam 110. Selector bars 10 and 11 are drawn to the right by their springs and any other selector bar that finds notches in the combination bars so aligned as to allow the projections thereunder to pass through a series of aligned notches is also drawn to the right.

Each selector bar 6 . . . 11 and 14 and 15 is provided with a pawl 6a . . . 11a and 14a, 15a pivoted to the selector bar and having two arms. These arms are held one upright and one horizontal, by a spring 6b . . . 11b and 14b, 15b. At the end of the horizontal arm of each pawl is a tooth 6c . . . 11c and 14c, 15c. When the selector bar is allowed to move to the right the tooth 6c . . . 11c and 14c, 15c rides past a tooth 6d . . . 11d and 14d, 15d on a corresponding secondary bar 6e . . . 11e and 14e, 15e. The bail 20 is then returned to the left by cam 110 and positively moves the selected selector bar to the left. The tooth 6c . . . 11c and 14c, 15c then catches the tooth 6d . . . 11d, 14d, 15d and carries the corresponding secondary bar 6e . . . 11e, 14e, 15e with it. The secondary bar 6e . . . 11e, 14e, 15e initiates the required function.

Each of the selector bars 6 . . . 15 (except bars 10 and 11) is provided with an upright projection 6h . . . 9h and 12h . . . 15h. This projection co-acts with two horizontal bars 21 and 22 which are pivoted at 24. When therefore a selector bar such as 6 is moved to the right the projection such as 6h thereon moves both bars 21 and 22 in an anti-clockwise direction. The bar 21 suppresses the printing function, and the bar 22 suppresses the spacing function when so moved as will presently appear.

The operation of the selection of certain functions will now be described.

Printing and letter space functions. (Fig. 2)

Selector bar 11 is the bar for the printing function and selector bar 10 that for the letter space function accompanying printing. When bail 20 moves to the right bars 10 and 11 are always drawn to the right, carrying with them pawls 10a and 11a. The upright arm of pawl 11a is high enough to co-act with bars 21 (bar 22 being cut away opposite said arm), as well as with a fixed bar 23 beneath the bars 21 and 22, whilst the upright arm of pawl 10a co-acts with the bar 22 only, bar 21 being cut away opposite pawl 10a.

When bail 20 is moved to the left and moves selector bars 10 and 11 to the left the teeth 10c and 11c on the horizontal arms of pawls 10a and 11a engage the teeth 10d and 11d on secondary bars 10e and 11e respectively and move secondary bars 10e and 11e to the left. Secondary bar 10e engages a lever 31 to release for rotation for one revolution cam 51 which is fixed to the same shaft as worm 108 and so rotates worm 108 which in turn rotates pinions 107 and 105 to move rack 106 by one letter space. Secondary bar 11e engages bell crank lever 32 which in turn rotates bell crank lever 52 clockwise and releases for rotation for one revolution a detent cam 53 and printing cam 109. The latter reciprocates the type wheel 102 against and away from platen 104. Bail 20 moves to the left beyond its normal position and as selector bars 10 and 11 reach the end of their travel the upright arms of pawls 10a and 11a engage the fixed bar 23 and disengage the teeth 10c and 11c from the teeth 10d and 11d

respectively and the secondary bars 10e and 11e are returned to their normal positions by their respective springs. Bail 20 moves back to its normal position and selector bars 10 and 11 follow it.

If the printing function is to be suppressed the upper bar 21 will have been moved in an anti-clockwise rotation and will engage the vertical arm of pawl 11a to rotate the pawl clockwise and prevent the tooth 11c engaging the tooth 11d on the secondary bar 11e. The secondary bar 11e will therefore not be carried to the left with the return movement of the bar 11. The bar 21 is cut with a notch opposite the upright arm of pawl 10a so that movement of bar 21 counterclockwise does not affect pawl 10a, but does rotate pawl 11a.

If the letter spacing function is to be suppressed bar 22 will have been moved counterclockwise and will act on pawl 10a to prevent movement of secondary bar 10e in the same manner as described above for the action of bar 21 in preventing movement of secondary bar 11e.

Figure shift and letter shift. (Fig. 1)

Selector bar 9 is for the figure shift function and is selected by a series of aligned notches in the combination bars 1 . . . 5. When bail 20 moves to the right therefore selector bar 9 can only follow it when allowed to do so by the combination set up on the bars 1 . . . 5. The projection 9h on selector bar 9 is of such height as to move both bars 21 and 22 anti-clockwise when selector bar 9 moves to the right and so suppresses both printing and letter spacing functions. The secondary bar 9e associated with selector bar 9 is provided with a downward projection 9i at its right-hand end, which engages with one arm of a three armed lever 40. Another arm of lever 40 is engaged by a similar downward projection 8i on the secondary bar 8e associated with the selector bar 8 for the letter shift signal. A third arm of the lever 40 engages between two uprights on a combination bar 25 arranged parallel to the combination bars 1 . . . 5.

When the selector bar 9 is selected and allowed to move to the right by bail 20 and the aligned slots in the bars 1 . . . 5, the tooth 9c on the pawl 9a engages behind the tooth 9d on the secondary bar 9e and when bail 20 moves to the left the secondary bar 9e is moved to the left and rotates the three armed lever 40. This latter then moves the bar 25 to the right.

The bar 25 is furnished, like bars 1 . . . 5, with a pivoted lever 100 and when rod 41 is moved downwards by cam 101 the hammer 56 on the lever 100 associated with bar 25 operates an additional sun and planet element to effect the figure shift function. The bar 25, like the bars 1 . . . 5, remains in the position into which it is set, until reset into opposite position.

The bars 1 . . . 5 and 25 are shown in Fig. 1 in their extreme left hand positions. These bars are formed with notches which co-act with projections on the underside of the selector bars (except 10 and 11) to allow of a certain selector bar being selected when the notches are in alignment with the projections. No attempt has been made in the drawings to show any particular arrangement of notches which will be in alignment for any particular code selection, the bars 1 . . . 5 being shown in position for the all-negative selection and the notches therein being shown aligned for the projections on all the selector bars 6 . . . 9 and 12 . . . 15. It will, how-

ever, be clear to anyone skilled in the art how the notches and projections are arranged since such arrangement is well known. It is clear that the bar 25 acts to select certain function selector bars which are only to be selected in the figure shift position.

It is to be noted that the upright portions of pawls 6a . . . 9a and 14a and 15a are of less height than those of pawls 10a and 11a and do not contact with the bars 21 and 22 but only with fixed bar 23.

Functions selected by three different signals. (Fig. 1)

15 Certain functions require for their selection three different signals in succession, viz, the figure shift signal, the "all negative" signal and a function signal. For this purpose a seventh combination bar 26 is provided, normally urged in one direction by a spring 57. The selector bar 7 is provided for the "all negative" signal, and when bail 20 moves to the right, this selector bar also moves to the right if selected by the setting of combination bars 1 . . . 5. When the bail 20 moves selector bar 7 to the left, the pawl 7a carries the secondary bar 7e to the left and a vertical projection 58 thereon engages one arm of a two-armed bell crank lever 59 and rotates it counter clockwise. The other arm of lever 59 engages combination bar 26 and moves it to the left against its spring 57. A pawl 60 mounted on a fixed portion of the machine has a tooth 61 which rests behind a tooth 62 on secondary bar 7e. Each time bail 20 reaches its extreme right hand position, pawl 60 is rotated counter clockwise and the tooth 61 thereon is moved away from tooth 62 on bar 7e. When bail 20 moves back to the left it allows pawl 60 to be rotated clockwise by its spring 63 and to come into position to engage the tooth 62 and when secondary bar 7e is released it is prevented from returning to normal position. The secondary bar 7e holds combination bar 26 in set position. The combination bar 26 then permits certain selector bars to move to the right following the next signal combination. Any selector bar associated with a function requiring the "all negative" signal is provided with a depending projection adapted to engage with the combination bar 26 in its unset position but to pass through a notch therein when it is held in set position.

40 The movement of the bail 20 to the right following the receipt of a signal after the "all negative" signal rotates pawl 60 out of engagement with tooth 62 so leaving secondary bar 7e free to be restored to normal position and thus restore combination bar 26 to normal position. Combination bar 26 is, however, held by the new selector bar having entered a notch therein, but when bail 20 moves to the left to initiate the required function, combination bar 26 is returned by spring 57 to normal position.

Functions selected by repetition of the same signal

65 Arrangements may be provided but are not shown in the drawing to enable a function to be selected by repetition of the same signal combination a number of times, for example, three. In such a case, the secondary bar (similar to the bar 7e) is provided with three teeth similar to tooth 7d adapted to engage with the pawl (such as 7a) carried by the selector bar, and with two teeth, similar to tooth 62 engaging with a pawl similar to pawl 60. Upon receipt of

the first signal the selector bar moves forward through an aligned series of notches in the combination bars 1 . . . 5, so that the pawl carried thereby picks up the first tooth on the secondary bar. The secondary bar is thus carried forward to the left and by engagement with the fixed pawl is held in that position. The secondary bar is of such a length that during this first movement it does not reach the associated function control lever. Upon receipt of the same signal combination a second time the secondary bar is moved forward through a second tooth space so that the end of the secondary bar is almost touching its function control lever, and is again held by the fixed pawl. Then upon receipt of the same signal combination a third time the secondary bar will be moved sufficiently far to engage and operate its associated function control lever.

If the signal combination is received once or twice and is then followed by a different combination the movement of the bail 20 to the right will release the pawl mounted on the frame of the apparatus from engagement with the secondary bar and the latter will be returned to normal position since it will not be engaged by the pawl on the selector bar.

Reciprocal functions

Functions which respectively initiate and terminate a particular control may be termed reciprocal functions. Figure shift and letter shift already described fall in this class. Other examples are release and arrest of a reperforating device. In the case of figure and letter shift the reciprocal action is ensured by an additional combination bar 25. In the case of the reperforator release and arrest, the reciprocal action is accomplished in a similar manner, as far as possible. Selector bars 15 and 14 (Fig. 4) are allotted to reperforator release and reperforator arrest respectively. The corresponding secondary bars 15e and 14e are provided with upright projections each engaging an arm of a three armed lever 64, the third arm 65 cooperating with a spring (not shown) whereby the lever is held in one or the other of two set positions. A fourth arm 66 is pivoted on the lever 64 and is held against a stop thereon by a spring. A third selector bar 16 is provided and furnished with a projection with which the arm 66 engages. The selector bar 16 has no projections on its underside but is provided with a pawl 16a and a secondary bar 16e in the same way as other selector bars.

Upon receipt of the reperforator release signal the selector bar 15 is selected and when the bail 20 moves to the right and then back to the left, the pawl 15a moves the secondary bar 15e to the left to rotate the three armed lever 64 and so move the arm 66 clear of the projection on the selector bar 16.

Any subsequent movement of the bail 20 to the right permits the selector bar 16 to move to the right and when the bail 20 moves to the left the pawl 16a moves the secondary bar 16e which acting upon a lever 67 releases a detent 68 to effect release of the reperforator.

When the reperforator arrest signal is received and bail 20 moves to the right the selector bar 14 will be allowed to move to the right, as well as selector bar 16, and when bail 20 moves to the left secondary bar 14e, as well as secondary bar 16e, will move to the left. The three armed lever 64 will be rotated to bring the arm 66 there-

on against the projection in selector bar 16 and this selector bar will thus be prevented from moving to the right upon subsequent movement of bail 20.

5 Spacing without printing (Fig. 3)

The spacing signal causes the selection of a selector bar 12 which does not carry a pawl and is not provided with a secondary bar. It is, however, provided with an upright projection 12h which is high enough to be opposite bars 21 and 22. Bar 22 is provided with a notch opposite projection 12h so that selector bar 12h in moving to the right does not move bar 22. Bar 21 is, however, moved and thus on selection of selector bar 12 printing is suppressed.

Printing without spacing (Fig. 3)

On the selection of some characters, such as an accent, it is desired to print the character but to suppress the spacing operation. The signal combination for such a character moves the combination bars 1 . . . 5 and possibly 25 to present a series of aligned notches to a selector bar 13 which does not carry a pawl and is not associated with a secondary bar. The upright projection 13h on the selector bar 13 moves the bar 22 anti-clockwise to engage the pawl 19a on the selector bar 10 to suppress the letter spacing function, but does not move the bar 21 to suppress the printing function since the bar 21 is furnished with a notch opposite projection 13h.

What is claimed is:

1. Printing telegraph receiver including a selector member, spring means for moving said member in one direction for function selection, means for moving said member in the other direction, and means actuated by the latter movement for initiating the performance of the selected function.

2. Printing telegraph receiver comprising a selector member for a function to be performed, a secondary member associated with the selector member, means for moving the selector member in one direction when the corresponding function is selected, means for returning the selector member in the reverse direction, means actuated by the selector member for moving said secondary member with it in the reverse direction and means actuated by the movement of said secondary member in said reverse direction for initiating the performance of said function.

3. Printing telegraph receiver comprising a bail member, means operable after the receipt of each signal to reciprocate said bail member, a plurality of selector members one for each function to be performed in the receiver, spring means for biasing each selector member toward said bail member, means for restraining said selector members against movement toward the bailed member, means for releasing a selected selector member arranged to permit the selected member to be drawn by an individual spring to follow the movement of said bail member in one direction and to be moved by said bail in its movement in the other direction and means operative on movement of the said selector member in the last mentioned direction to initiate the performance of the required function.

4. Printing telegraph receiver as claimed in claim 3 including means for invariably selecting the selector members for the printing function and the letter space function accompanying printing at each reciprocation of said bail, combination bars arranged for selection of selector members

for other functions, means effective on the selection of a selector member for one of said other functions to prevent the movement of the selector member for at least one of said printing and letter space functions from being effective in initiating the performance of its corresponding function.

5. Printing telegraph receiver as claimed in claim 3 including a secondary member associated with each of a plurality of selector members and means for causing the selector member when moved in one direction to move with it its associated secondary member and means for causing said last mentioned movement of said secondary member to initiate the performance of a function.

6. Printing telegraph receiver as claimed in claim 2 including a pawl pivoted on a selector member and a cooperating abutment on said secondary member arranged for engagement by the pawl during movement of said secondary member in reverse direction arranged to move said secondary member in said reverse direction.

7. Printing telegraph receiver as claimed in claim 1 comprising combination bars, one for each element of a received signal, means for setting said combination bars in accordance with the respective elements of a signal, selector members lying transversely of said combination bars complementary means on the combination bars and selector members arranged to enable selector members selected by a particular setting of said combination bars to move relatively to said combination bars.

8. Printing telegraph receiver comprising a plurality of combination bars, one for each element of a received signal, means for setting said combination bars in accordance with the respective elements of such signal, longitudinally movable selector members lying transversely of said combination bars, complementary means on said selector and combination bars arranged to release a selected selector member for longitudinal

movement, means for imparting to such released bar an advance and return movement, and means actuated by said released bar during the return movement for initiating a function of said receiver.

9. Printing telegraph receiver as claimed in claim 8 in which the complementary means includes notches in said combination bars and projections on said selector members arranged to engage the combination bars and prevent lengthwise movement of the selector bars except when each projection on a selector bar is in alignment with a notch in the adjacent combination bar.

10. Printing telegraph receiver comprising a plurality of combination bars, means for positioning said bars in accordance with the elements of a received signal, a plurality of selector bars, means for moving the selector bars to initiate functions of the receiver controlled by the setting of the combination bars, and means for preventing a selector bar from initiating such function including a member movable into engagement with such selective bar during its movement by said moving means.

11. Printing telegraph receiver as claimed in claim 10 including selector bars for initiating the printing and letter spacing functions respectively, said preventing means including means actuated by another selector bar for selectively preventing the operation of said printing selector bar and letter spacing selector bar respectively.

12. Printing telegraph receiver as claimed in claim 2, including a function actuating member, and means for shifting said member into and out of operation including means actuated by a secondary member for shifting said means into actuating position and means associated with another secondary member for shifting said actuating means out of actuating position.

REGINALD DENNIS SALMON.
